EXAMINATION TABLE FOR VETERINARIANS

Alden C. Dirck, 1020 W. Winona Ave.,
Warsaw, Ind. 46580

Filed Apr. 25, 1974, Ser. No. 464,252

Term of patent 14 years

Int. Cl. D24—01

U.S. Cl. D83—1 D

Fig. 1

Fig. 2

Fig. 3

FIG. 1 is a perspective view of an examination table for veterinarians showing my new design;

FIG. 2 is a front elevational view thereof; and

FIG. 3 is a side elevational view thereof.

The rear of the examination table is substantially un-ornamented.

I claim:

The ornamental design for an examination table for veterinarians, as shown and described.
